TRICHOMONADICIDAL THERAPEUTIC
COMPOSITIONJ. Garth Johnson, Bound Brook, N. J., assignor to
Ortho Pharmaceutical Corporation, a corpora-
tion of New JerseyNo Drawing. Application June 11, 1946;
Serial No. 676,103

9 Claims. (Cl. 167—58)

1

The present invention relates to a new and improved therapeutic composition for the treatment of certain protozoan infections, and more particularly to a novel and highly effective pharmaceutical preparation designed for the clinical control of *Trichomonas vaginalis* infestations.

Trichomonas vaginalis is a genito-urinary parasite which primarily infests the mucous membrane of the human vagina and cervix, being associated with, and probably the cause of, a very troublesome and prevalent form of infestation known as *Trichomonas vaginalis* vaginitis. While the organism is harbored primarily in the vagina, it also affects the urethra, bladder, and the ducts of the Bartholin's glands of the female, as well as the urethra, bladder, and possibly the prostate of the male.

Conservative estimates have placed the incidence of the infestation in the female at about 20 to 40 per cent in the unselected population the world over, with a somewhat higher incidence in the colored race. In the male, the incidence of *Trichomonas* infestation is estimated to be approximately 15 per cent of the unselected population with an incidence of about 34 per cent in cases of non-specific prostatitis.

One of the major problems in the control of *Trichomonas vaginalis* vaginitis arises from the recurrence of infection following apparent clinical cure. These recurrences in the female may be due to reinfection from the female urinary tract, from ducts of the associated vaginal glands or from contact with an infected sexual partner. The clinical control of the infection therefore includes topical medication of the vagina per se and treatment of the urethra and bladder in both sexual partners, as well as medication of the ducts of the associated vaginal glands.

Various medicaments and methods of treatment have heretofore been employed in the treatment of *Trichomonas vaginalis* vaginitis, but all of these have been subject to numerous limitations and disadvantages. Thus, for example, the commonly used organic acids such as acetic, lactic, and citric acids, are characterized by very low trichomonadicidal action, and in many instances they fail satisfactorily to clear up the infestation, even when the therapy is continued for long periods of time. Other agents such as silver picrate have high trichomonadicidal properties but are objectionable for the reason that they give rise to severe sensitizations, argyria and the like, and also because they produce aesthetically unacceptable stains. The phenyl mercuric compounds, such as the nitrate or acetate, are likewise, exceedingly active trichomonadicidal compounds, but they are reported to be unstable except at a limited pH range (7.4 to 7.6) which differs considerably from that likely to be encountered in an infested vagina. Still other

preparations using various agents in the powdered form for medication by the insufflation technique (e. g., boric acid, diiodoquinone, lactose, and dextrose, as well as silver picrate) are open to serious criticism on the basis of numerous air embolisms resulting in death following insufflation of pregnant women. For these and other reasons, a more satisfactory trichomonicide has long been desired.

10 The object of the present invention is to provide a new and improved therapeutic preparation and technique for the treatment of *Trichomonas vaginalis* infestations, with a view to obviating the disadvantages of the medicaments and modes of treatment heretofore employed.

A more particular object is the provision of a therapeutic composition characterized by high trichomonadicidal power and capable of effecting the rapid destruction of the parasites without causing irritation of the human tissue, including the vaginal mucosa.

Still another object is the provision of a composition of the character described which is free of any adverse side reactions upon the patient; is safe for home use by the patient following office treatment by the physician; is characterized by a high degree of efficacy in the treatment of *Trichomonas vaginalis* vaginitis; and is free of unaesthetic staining tendencies when used for the purpose intended.

Other objects and advantages of the invention will become apparent as the description progresses.

The foregoing objects may be attained in accordance with the present invention which is based in part upon two correlative discoveries; namely (1) that bromoacetic acid and its water-soluble salts (hereinafter collectively referred to as "bromoacetic acid compounds") are characterized by an extraordinarily high trichomonadicidal action that is many times greater than that of the organic acids heretofore most commonly employed in the treatment of *Trichomonas vaginalis* infestations; and (2) that, although bromoacetic acid compounds in concentrated form are vesicant to human tissue, nevertheless, because of their extremely potent trichomonadicidal action, they may be employed as effective trichomonicides by incorporating them in a suitable therapeutic vehicle in concentrations so low that the resulting compositions are essentially non-irritant to the most sensitive human tissues including the vaginal mucosa. The trichomonadicidal compositions of the present invention therefore comprises one or more bromoacetic acid compounds, uniformly distributed throughout a suitable pharmaceutical vehicle, the acid compound being present in the vehicle in a proportion sufficient to impart trichomonadicidal properties

2

to the composition, but insufficient to render the composition irritant to sensitive human tissue.

The trichomonadicidal potency of bromoacetic acid and its soluble salts was established by extensive investigations which demonstrated that they constitute highly effective agents even used in concentrations far below 1 part of acid compound in 1000 parts of vehicle. Indeed, the preparations to be described in detail hereinafter have "effective dilutions" ranging from approximately 1:10,000 to 1:45,000, the "effective dilution" being defined as the maximum dilution (expressed in terms of the effective agent) at which the composition is capable of destroying *Trichomonas* in 10 minutes, but not in 5, in the presence of 25 per cent human serum, when tested in vitro by the standard procedure described by Johnson and Trussell, Proceedings of The Society for Experimental Biology and Medicine, vol. 54, pp. 245-249, 1943. This extremely high activity of bromoacetic acid and its salts is to be compared with that of acetic acid, for example, which has an "effective dilution" of only 1 part in 256, or with that of lactic acid, which has an "effective dilution" of only 1 part in 213. In other words, under the conditions of the Johnson and Trussell test, the trichomonadicides of this invention are roughly 45 to 200 times as active as the agents heretofore most commonly used in the treatment of *Trichomonas vaginalis*.

The non-irritancy of bromoacetic acid at effective concentrations was established by rigorous tests which demonstrated that this acid, when used in a suitable chemotherapeutic vehicle in concentrations as high as 1 part by weight of acid to 700 parts by weight of vehicle, produces no objective signs of local tissue irritation of the human vaginal mucosa, except in an exceedingly small percentage of cases of special drug sensitivity. The acid can probably be used without irritancy at significantly higher levels of concentration; however concentrations above 1 part in 1000 are not required for effective trichomonadicidal potency, and I prefer to use the bromoacetic acid compound in concentrations ranging from about 1:1000 to about 1:10,000 although, as previously indicated, concentrations from about 1:700 to about 1:100,000 are useful and effective under certain conditions.

In employing the trichomonadicides in the present invention for the treatment of vaginal infestations, one or more of the active agents are uniformly distributed in a suitable chemotherapeutic vehicle that is chemically compatible with the particular trichomonadicide selected, non-inhibiting with respect to the action of the effective agent upon the parasite, and essentially non-injurious to the vaginal mucosa under the conditions of use. Since it is desirable to avoid the previously mentioned hazards arising from the insufflation of powdered materials, the vehicle is preferably of a liquid or semi-liquid type. Furthermore, since the final preparation should be readily miscible with the vaginal fluids, the vehicles, whether hydrous or anhydrous in character, should nevertheless be of the water-miscible or water-dispersible type.

The foregoing criteria may be met by a large number of liquid or semi-liquid chemotherapeutic vehicles that are well known in the art. Thus for example, the vehicle may consist merely of a simple, non-injurious water-miscible solvent, such as water itself, or any of the various water-soluble glycols, such as propylene glycol, for example; or it may comprise a mixture of such

solvents, the resulting solution being employed as a vaginal douche. For several reasons, however, it is much more desirable to employ water dispersible liquid or semi-liquid vehicles that are colloidal in nature, particularly those that are viscous and/or mucilaginous in character. This preference is based in part upon the fact that, in the topical treatment of infestations of the vagina and external genitalia, a preparation that is gelatinous or mucilaginous in character will afford prolonged contact between the medicament and the parasite. A further and possibly even more important reason for the preference mentioned is based upon the discovery that the trichomonadicidal potency of a given bromoacetic acid compound, when dispersed in all the colloidal vehicles investigated, is substantially greater than the potency of the same agent when used in the same concentrations in solution in non-colloidal vehicle such as water. Accordingly, by employing a colloidal vehicle, concentrations far below the irritant level for bromoacetic acid and its compounds may be used.

Of the various types of water-dispersible, viscous colloidal gels or emulsions that may be used as suitable colloidal vehicles for the trichomonadicides of the present invention, particular mention may be made of the well known oil-in-water types of emulsions or creams as well as the equally well known aqueous jells such as those prepared with the aid of various jelling agents, for example, acacia, tragacanth, bentonite, alginic acid and the like. The preferred vehicle, however, comprises a viscous, aqueous jell containing pectin as a jelling agent, inasmuch as the presence of pectin in the finished composition, for reasons at present not understood, appears to enhance the trichomonadicidal potency of bromoacetic acid compounds to an outstanding degree.

In order more clearly to disclose the nature of the present invention, several specific examples will hereinafter be described in considerable detail. It should be understood that these are presented solely for purposes of illustration and not with the object of either delineating the scope of the invention or restricting the breadth of the appended claims.

EXAMPLE I

This example is illustrative of one of the preferred embodiments of the invention—namely, a water-dispersible aqueous gel containing pectin and bromoacetic acid, the latter at a 1:1000 dilution. The complete formulation is as follows:

	Per cent
(A) Pectin powder N. F. VII.	6.5
(B) Methyl cellulose (Dow "Methocel") 1500 cps	0.75
(C) Propyl p-hydroxy benzoate	0.05
(D) Bromoacetic acid	0.1
(E) Deionized water to	100

The gel may be prepared by either of the following two methods:

Method A

I. Heat the water to about 90° C., add the propyl-p-hydroxy benzoate and stir until dissolved.

II. Dissolve the bromoacetic acid in a small proportion (e. g., 1%) of solution I.

III. Add the methyl cellulose to the remainder of solution I, heated to 90° C., stir for 20 minutes and then cool to 25° C., stirring constantly.

IV. When solution III is cooled to 25° C., add the pectin powder, slowly and with constant agitation.

V. Add to the pectin-containing mixture IV, the bromoacetic acid solution II, then stir for 30 minutes, let it stand for 12 hours, and finally mix for 10 minutes before packaging the gel in any suitable container such as a collapsible tube.

Method B

I. Heat the water to about 90° C., add propyl-p-hydroxy benzoate and mix until dissolved.

II. Remove 50% of the solution from the mixing vessel (portion A). Cool the 50% of the solution remaining in the mixing vessel (portion B), to 25° C., add the pectin powder with agitation and stir until dissolved.

III. To 40% of withdrawn portion A, at 90 to 95° C., add the methyl cellulose and stir for 20 minutes.

IV. Add 40% of withdrawn portion A, cooled to 4° C., to III.

V. Mix II and IV for 30 minutes, with continuous agitation.

VI. Dissolve bromoacetic acid in 20% of portion A and add to V; stir for 30 minutes, let it stand for 12 hours, and finally mix for 10 minutes before packaging in any suitable container.

The product produced by either of the above methods is a clear, smooth, viscous gel that is admirably adapted for the topical treatment of infestations of the vagina and external genitalia.

EXAMPLE II

This example illustrates a formulation containing bromoacetic acid in an aqueous-base cream-like vehicle. The composition of the finished cream is as follows:

	Per cent
(A) Glyceryl monostearate	9.0
(B) Stearic acid	6.0
(C) Peanut oil	5.0
(D) Glycerin	5.0
(E) Triethanolamine	0.5
(F) Bromoacetic acid	0.0125
(G) Distilled water, to make	100.0000

The cream may be prepared as follows:

I. Place the oleaginous ingredients (A, B, and C) in a suitable vessel, heat the contents until all the ingredients are melted, mix thoroughly, and adjust the temperature to about 70° C.

II. Then slowly and with rapid agitation, add the resulting mixture to all but a small proportion of the water to be used, warmed to about 70° C., continue the agitation for about 1/2 hour, until a cream-like emulsion is formed and cool the emulsion to about 50° C.

III. Then add the bromoacetic acid (F), dissolved in about 5% of the total water to be used, to the cream-like emulsion at about 50° C., and agitate continuously until a uniform composition is obtained. Cool the product to about room temperature and package it in suitable containers. The product is a smooth, water-dispersible emulsion resembling cold cream in consistency.

EXAMPLE III

This formulation is a cream similar to that of Example II, except as regards the particular bromoactive acid compounds employed; in this case, the sodium salt is used instead of the free acid. The vehicle is the same as that used in Example II.

The composition of the finished cream is as follows:

	Percent
(A) Glyceryl monostearate	9.0
(B) Stearic acid	6.0
(C) Peanut oil	5.0
(D) Glycerin	5.0
(E) Triethanolamine	0.5
(F) Sodium bromoacetate (1:4000)	0.025
(G) Distilled water, to make	100.000

The cream may be prepared by the procedure described in Example II. Its properties are similar to those of the corresponding bromoacetic acid cream. Any other water-soluble bromoacetic acid salt (for example the potassium salt) may be used in place of the sodium salt.

EXAMPLE IV

This example illustrates a formulation containing bromoacetic acid in an anhydrous water-dispersible gel having a propylene glycol base, thickened with high molecular weight polyethylene glycols (mol. wt. about 4000), methyl cellulose, and sterols in an absorption base.

The composition of the finished gel is as follows:

	Percent
(A) Bromoacetic acid 1:1000	0.1
(B) Methyl cellulose—1500 cps	1.0
(C) Propylene glycol N. F. VII	61.9
(D) Polyethylene glycols ("Carbowax") 4000	25.0
(E) Cholesterol concentrate ("Amerchol")	12.0

The gel may be prepared as follows:

I. Melt the cholesterol concentrate (sterols in an absorption base) and polyethylene glycol ("Carbowax") at about 70° C.

II. Add the methyl cellulose to I and stir the mixture for about 20 minutes, the temperature at this stage being about 50° C.

III. Dissolve the bromoacetic acid in the propylene glycol at a temperature of about 40° C. and add the resulting solution to the above mixture (II).

IV. Heat the mixture III to about 50° C. and pass it through a colloid mill. The resulting product is a viscous, water-dispersible colloidal gel.

EXAMPLE V

This example illustrates a formulation similar to that of Example IV except for variations in the formula and the method of preparation.

The composition of the finished gel is as follows:

	Percent
(A) Methyl cellulose (Dow) 25 cps	2.5
(B) Propylene glycol N. F. VII	64.4
(C) Polyethylene glycol ("Carbowax") 4000	21.0
(D) Cholesterol concentrate ("Amerchol")	12.0
(E) Bromoacetic acid	0.1

The gel may be prepared as follows:

I. Dissolve the methyl cellulose (A) in about 60% of the propylene glycol (B), with a vigorous agitation.

II. Heat the polyethylene glycol (C) with the cholesterol concentrate (D) on water bath till both are melted.

III. Add the melted polyethylene glycol-cholesterol mixture to the propylene glycol-methyl cellulose mixture. Continue stirring till a uniform dispersion is obtained.

IV. At 45° C. add the bromoacetic acid (E) dissolved in the balance of the propylene glycol (B).

V. Allow the mixture to stand 12 hours, and then pass it through a colloid mill. The resulting composition is a viscous, water-dispersible colloidal gel.

EXAMPLE VI

This example illustrates a formulation containing bromoacetic acid in an anhydrous gel prepared from low molecular weight polyethylene glycols (mol. wt. about 300), thickened with high molecular weight polyethylene glycols (mol. wt. about 4000), polyvinyl alcohol and cholesterol in an adsorption base.

The composition of the gel is as follows:

	Per cent
(A) Water-soluble polyvinyl alcohol (med. visc.)	0.5
(B) Polyethylene glycol ("Carbowax") 4000	25.0
(C) Polyethylene glycol (300)	66.40
(D) Cholesterol concentrate	8.0
(E) Bromoacetic acid	0.1

The gel may be prepared as follows:

I. Heat the polyethylene glycol 4000 and cholesterol concentrate together, and adjust the temperature to about 60° C.

II. Heat about 99% of the polyethylene glycol 300 to about 60° C., then add the polyvinyl alcohol and stir until the latter swells.

III. Mix I and II for about 20 minutes, then cool to about 25° C.

IV. Add the bromoacetic acid, dissolved in about 1% of the polyethylene glycol 300, to III.

V. Pass the resulting composition through a colloid mill twice. The resulting composition is a viscous, water-dispersible colloidal gel.

EXAMPLE VII

This example illustrates a formulation containing bromoacetic acid in an anhydrous base prepared from propylene glycol, thickened with both low and high molecular weight polyethylene glycol (mol. wt. about 300 and 4000 respectively), polyvinyl alcohol and cholesterol concentrate.

III. Add I and II and mix thoroughly.

IV. Add the polyethylene glycol 300 and the bromoacetic acid, dissolved in the remaining 25% of propylene glycol, to III.

V. Pass the resulting mixture through a colloid mill twice. The resulting product is a viscous, water-dispersible colloidal gel.

EXAMPLE VIII

10 This example illustrates a formulation using a bentonite-water cream as the vehicle. The composition of the finished cream is as follows:

	Per cent
(A) Micronized bentonite	15
(B) Bromoacetic acid	0.1
(C) Deionized water to	100.00

The cream may be prepared by adding the bentonite slowly to water and then thoroughly homogenizing the mixture to form a gel or cream.

20 The bromoacetic acid, dissolved in a small proportion of the water, is then thoroughly mixed in the bentonite gel. The resulting product is a viscous, colloidal cream having an effective dilution of about 1:20,000, or more than twice that of a simple aqueous solution of the same concentration with respect to bromoacetic acid.

Trichomonadicidal potency

30 Table I summarizes the results of tests carried out in accordance with the standard procedure of Johnson and Trussell (loc. cit.), in order to determine the "effective dilution" of certain trichomonadicidal preparations in accordance with the present invention. In this table, the dilution figures given in the fourth column are representative of the sensitivity of the Trussell strain of *Trichomonas vaginalis* to the various test preparations, the composition of which is indicated in the second and third columns. From the data given in this table, the enhanced trichomonadicidal potency of the colloidal compositions, compared to that of a simple aqueous solution of the same concentration, will be apparent.

Table I

Test No.	Conc. of Bromoacetic Acid Comp'd in Test Composition	Type of Vehicle used in Test Composition	"Effective Dilution"
A	0.01% (acid)	water alone	1:7500
B	do	pectin-containing aqueous gel as in Example I	1:15,000 to 1:45,000
C	0.0125% (acid)	oil-in-water emulsion or cream, as in Example II	1:40,000
D	0.025% (sod. salt)	same as in C, and Example III	1:12,000 to 1:20,000
E	0.01% (acid)	anhydrous jell as in Example IV	1:20,000
F	do	anhydrous jell as in Example V	1:10,000
G	do	anhydrous gel as in Example VII	1:10,000
H	do	bentonite-water cream as in Example VIII	1:20,000

The composition is as follows:

	Per cent
(A) Water-soluble polyvinyl alcohol (med. visc.)	0.5
(B) Polyethylene glycol — 4000 ("Carbowax")	21.0
(C) Cholesterol concentrate ("Amerchol")	12.0
(D) Propylene glycol, N. F. VII	10.0
(E) Polyethylene glycol (300)	51.4
(F) Glycerin, C. P.	5.0
(G) Bromoacetic acid	0.1

The gel may be prepared as follows:

I. Mix the polyvinyl alcohol and the glycerin until evenly dispersed. Then add about 75% of the propylene glycol.

II. Melt the polyethylene glycol 4000 and cholesterol concentrate at about 70° C.

60 The chemotherapeutic compositions in accordance with the present invention are preferably applied to the vagina by means of a vaginal applicator of the type commonly used for contraceptive preparations. Approximately 5 cc. of the material is placed within the vagina per application, and a small amount is topically applied to the external genitalia. Two applications daily, morning and evening, are recommended with continuous medication for a period of four weeks, including, if possible, the menstrual period. The results observed are the immediate disappearance of clinical symptoms with complete eradication of the parasites from the vagina following the first 15 to 30 days of treatment.

75 It will be apparent to those skilled in the art

that numerous variations, modifications, and extensions of the principles involved may be made without departing from the spirit and scope of the invention. Thus, for example, the pharmaceutical vehicles employed in the various examples are merely illustrative and it will be apparent that many other colloidal pharmaceutical vehicles may be used in place of those illustrated in the examples. Likewise, water-soluble bromoacetic acid compounds other than those specifically mentioned may be used either singly or in combination. All such variations, modifications, and extensions are to be understood as included within the ambit of the appended claims.

I claim as my invention:

1. A therapeutic composition adapted for the treatment of *Trichomonas vaginalis* vaginitis comprising a member of the group consisting of bromoacetic acid and its water-soluble salts as the effective trichomonadicidal agent, uniformly distributed in a water-dispersible, colloidal therapeutic vehicle that is compatible with said bromoacetic acid compound and essentially non-irritating to human tissue, said bromoacetic acid compound being present in said composition to the extent of not more than about 1 part by weight to 700 parts by weight of said vehicle.

2. The composition of claim 1 wherein said vehicle comprises an anhydrous colloid.

3. The composition of claim 1 wherein said vehicle comprises a cream-like aqueous oleaginous emulsion.

4. The composition of claim 1 wherein said vehicle comprises a gelatinous colloid.

5. A therapeutic composition adapted for the treatment of *Trichomonas vaginalis* vaginitis comprising a member of the group consisting of bromoacetic acid and its water-soluble salts as the effective trichomonadicidal agent uniformly distributed in a water-dispersible, pectin-containing, gelatinous, colloidal gel, said bromoacetic acid compound being present in the said composition to the extent of not more than about one part

by weight to 700 parts by weight of said vehicle.

6. A therapeutic composition adapted for the treatment of *Trichomonas vaginalis* vaginitis, comprising a member of the group consisting of bromoacetic acid and its water-soluble salts as the effective trichomonadicidal agent, uniformly distributed in a water-dispersible, gelatinous therapeutic vehicle containing pectin and a water-dispersible, gel-stiffening agent adapted to increase the mucilaginous character of said vehicle, said bromoacetic acid compound being present in said composition to the extent of not more than about one part by weight to 700 parts by weight of said vehicle.

15 7. The composition of claim 6 wherein said gel-stiffening agent comprises water-soluble methyl cellulose.

8. The composition of claim 6 wherein said gel-stiffening agent comprises polyvinyl alcohol.

20 9. The composition of claim 6 wherein said composition also contains a small proportion of a fungicidal agent.
